US00D599433S

(12) **United States Design Patent**
Zore

(10) **Patent No.:** **US D599,433 S**
(45) **Date of Patent:** **** Sep. 1, 2009**

(54) **NOZZLE**

(75) Inventor: **William Francis Zore**, Friedens, PA
(US)

(73) Assignee: **Robert Bosch GmbH**, Stuttgart (DE)

(**) Term: **14 Years**

(21) Appl. No.: **29/326,938**

(22) Filed: **Oct. 28, 2008**

(51) **LOC (9) Cl.** **23-01**

(52) **U.S. Cl.** **D23/223**

(58) **Field of Classification Search** **D23/213, D23/223, 226; 239/525-526, 532**

(74) *Attorney, Agent, or Firm*—Maginot, Moore & Beck

(57) **CLAIM**

The ornamental design for a nozzle, as shown and described.

DESCRIPTION

FIG. 1 is a perspective view a nozzle showing my new design;

FIG. 2 is a left side elevational view showing the design for the nozzle of FIG. 1;

FIG. 3 is a right side elevational view showing the design for the nozzle of FIG. 1;

FIG. 4 is a front elevational view showing the design for the nozzle of FIG. 1;

FIG. 5 is a rear elevational view showing the design for the nozzle of FIG. 1;

FIG. 6 is a top elevational view showing the design for the nozzle of FIG. 1; and,

FIG. 7 is a bottom elevational view showing the design for the nozzle of FIG. 1.

The broken lines showing of portions of the nozzle is included for illustrative purposes only and forms no part of the claimed design.

1 Claim, 5 Drawing Sheets
